UNITED STATES PATENT OFFICE.

PETER KERZE, OF ELY, MINNESOTA.

METAL TIE.

1,204,279.

Specification of Letters Patent.

Patented Nov. 7, 1916.

Application filed March 14, 1916. Serial No. 84,147.

To all whom it may concern:

Be it known that I, PETER KERZE, a citizen of the United States, residing at Ely, in the county of St. Louis and State of Minnesota, have invented new and useful Improvements in Metal Ties, of which the following is a specification.

This invention relates to improvements in the construction of metal ties.

10 In carrying out my invention it is my purpose to construct a metal tie of two members each of a trough-like formation, each provided with transverse members or partitions, the partitions in one of the sections 15 having projecting members forming tongues, the partitions in the other member having depressions providing pockets to receive the tongues, and a single bolt arranged central of the sections and intermediate of the partitions passing through both of the sections 20 and connecting the sections.

It is also my purpose to construct a metal tie comprising two hollow sections one arranged upon the other, partitions having 25 interengaging means dividing the sections of the ties into a central and into outer compartments, the said outer compartments adapted to receive the roadbed to sustain the tie against side movement, a single element 30 connecting the sections and the upper section being provided with threaded openings and with depressions disposed adjacent the openings whereby bolts may be received in the said threaded openings and the lugs of 35 rail engaging elements received in the said depressions to hold the said rail engaging elements upon the tie.

With the above and other objects in view, the improvement resides in the construction, 40 combination and arrangement of parts set forth in the following specification and falling within the scope of the appended claims.

In the drawings, Figure 1 is a perspective view of ties constructed in accordance with 45 the present invention and showing the rails supported thereon, Fig. 2 is a top plan view of one of the ties with the rails and the rail securing elements removed therefrom, Fig. 3 is a sectional view approximately on 50 the line 3-3 of Fig. 1, Fig. 4 is a transverse sectional view approximately on the line 4-4 of Fig. 2, Fig. 5 is a perspective view of one of the rail securing elements looking toward the underface thereof, Fig. 6 is a 55 perspective view of the lower section of the ties, and Fig. 7 is a similar view of the

upper section, looking toward the bottom thereof.

The tie comprises an upper trough-shaped member 1 and a lower trough-shaped member 2. The members are, of course, of an equal length and width and their sides or flanges 3-3 are adapted to rest one on the other. Each of the members at a suitable distance from its end is formed with an integral transverse partition 4-4, the same dividing the tie into a central compartment and into end compartments. The partitions 4 of the lower section 2 are formed with upwardly extending tongues 5 and the partitions 4 of the upper section 1 are provided with depressions 6 which form pockets to receive the tongues 5. The tongues are substantially rectangular in cross section and are snugly received in the pockets so that a swinging movement of the upper section on the lower section or a longitudinal movement of either of the sections will be thus prevented. Passing through a central opening in both of the sections is a connecting member in the nature of a bolt 6, the head of the bolt resting against the base of the lower section and its threaded shank projecting above the top of the upper section, and locking elements in the nature of nuts 7 are provided for the bolt.

The end compartments, it will be noted, are arranged to receive the ballast of the roadbed, and if desired this ballast may be 90 also positioned in the central compartment so that the tie will be thus effectively held against side or longitudinal movement when the roadbed has been properly tamped around the same.

The horizontally straight top of the section 1 at a suitable distance from the ends thereof is provided with bolt openings 8-8, the same being arranged a suitable distance apart and the said top, outward of the bolt openings, is formed with depressions 9. These depressions are adapted to receive the lugs 10 on rail engaging elements 11, while bolts 12 pass through openings in the said members 11 and are received in the referred to threaded openings 8. By this means it will be noted that rail elements of various classes, but which are all provided with lugs 10, may be easily and quickly secured to or removed from the tie.

From the above description, taken in connection with the accompanying drawings,

the simplicity of the device, as well as the advantages thereof will, it is thought, be perfectly apparent to those skilled in the art to which such invention appertains 5 without further detailed description.

Having thus described the invention, what I claim is:

1. A metal tie comprising two similar trough-shaped members adapted to have 10 their edges rest one on the other, each of the members having transverse partitions, the partitions in one of the members having extending tongues and the partitions of the other member having pockets to receive the 15 tongues, and means for connecting the members.

2. In a metal tie, two trough-like members having their edges resting one upon the other, each of the members adjacent its 20 ends having transverse partitions, the partitions upon one of the members having projecting tongues, the partitions of the other member having pockets to receive the tongues, and a single element passing 25 through sections centrally thereof for connecting the said sections.

3. In a metal tie, two similar sections, each including a straight member having its sides formed with right angular flanges, and the edges of the flanges resting one upon 30 the other, each of the members having integral transverse partitions, the partitions of one of the members being formed with 35 extending tongues, the partitions of the other member being recessed to provide pockets to receive the tongues, a single element passing centrally through the members for connecting the same, the upper member having its top provided with threaded openings and with depressions disposed outward of the openings, whereby bolt members passing through rail engaging elements may connect the elements to the ties and retain lugs provided in the said elements in the depressions in the tie. 40 45

In testimony whereof I affix my signature in presence of two witnesses.

PETER KERZE.
